UNITED STATES PATENT OFFICE.

THADDEUS R. BAKER, OF INDIANAPOLIS, INDIANA.

MEANS FOR ATTACHING BOLSTER-SPRINGS.

1,108,316.

Specification of Letters Patent. Patented Aug. 25, 1914.

Application filed March 25, 1914. Serial No. 827,152.

To all whom it may concern:

Be it known that I, THADDEUS R. BAKER, a citizen of the United States, residing at Indianapolis, in the county of Marion and

5 State of Indiana, have invented certain new and useful Improvements in Means for Attaching Bolster-Springs, of which the following is a specification.

The object of this invention is to provide 10 means for securing conical springs to wagon bolsters, between the latter and the bed or load-carrying portion of a vehicle, in a removable manner in order to provide a ready means for converting a springless wagon 15 into one wherein the load will be spring supported. I accomplish the above object by the means illustrated in the accompanying drawing, in which—

Figure 1 is a perspective view of a wagon 20 bolster with my invention shown in operative position thereon, and Fig. 2 is a top plan view of one end of the same bolster and spring mechanism illustrated in Fig. 1, with the exception that the upper horizontal plate 25 is removed.

Like characters of reference indicate like parts throughout the several views of the drawing.

The bolster 3 for either the front or rear 30 axle of any desired and well known form of wagon is of the usual construction and the load-supporting bed or platform, which is usually supported upon the bolster between the standards 4, is not shown.

35 Conical springs 5, here shown as two in number and of usual construction, are fastened upon a base-plate 6. The base-plate 6 is of metal of approximately the same width as the top of the bolster and extends 40 from one standard 4 of the bolster to the other and sufficiently beyond each standard to form a locking notch which will receive and hold the standard when the metal in the end of the plate is removed for this purpose.

45 The metal where the notches for the standards are formed is removed for the reception of the standards by being bent into a loop toward the middle of the plate but is not detached at its inner end from the plate.

50 The loop 7 thus formed is bent around a cross-bar 8 formed in a base-extension 9 of the spring 5. The length of the base-extension 9 is sufficient to position the conical spring 5 suitably remote from the standard 4

55 to properly support the load and afford a suitable bearing for spring 5.

The material of the spring 5 is further continued beyond the cross-bar 8 but in a direction causing it to pass under the bottom convolution of spring 5 forming a member 60 10 upon which the spring 5 rests and by which it is partially supported. The member 10 is continued substantially the same distance on the other side of the spring 5 toward the middle of the bolster and is bent 65 to form a second cross-bar 11 which is held under a loop 12 formed out of a tongue punched up from the material of the plate 6. The cross-bar 11 terminates in an end hook 70 13 which prevents the longitudinal withdrawal of the cross-bar from loop 12.

A bearing plate 14 similar to the plate 6, with its ends notched in like manner to engage the standards 4 is loosely positioned between said standards upon the pair of 75 springs 5. This plate is a metal one and is principally for the purpose of protecting the wooden wagon bed, to be supported by the springs, from wear. The mechanism above described, including the plate 14 as 80 shown in Fig. 1, is ready to receive the wagon bed or other load-supporting member of the wagon which is placed upon the plates 14 between the standards 4 in substantially the same manner as it was previously placed in direct contact with the bolsters.

It is obvious that my invention is readily removable and can be used when desired or required and at other times can be omitted. 85

90 While I have described my invention with more or less minuteness as regards details of construction and arrangement and as being embodied in certain precise forms, I do not desire to be limited thereto unduly or any more than is pointed out in the claims. On the contrary, I contemplate all proper changes in form, construction and arrangement, the omission of immaterial elements, and the substitution of equivalents, as circumstances may suggest or necessity render 95 expedient.

I claim:

1. In a device for the purposes specified, a base-plate, one or more coiled springs 105 mounted on said plate, each spring having an extension of its lower end made in the direction of the adjacent standard and bent near the standard to form a cross-bar transverse to the bolster, said extension passing thence under the bottom convolution of the spring and supporting the 110

- latter on the opposite side of the bolster from the starting place of said spring extension and thence continued and bent to form a second cross-bar resting upon the
5 bolster upon the opposite side of the spring from said first cross-bar, and loops formed out of the material of the base-plate engaging said spring base-extensions whereby the latter are secured to the base-plate.
- 10 2. In a device for the purposes specified, a base-plate, one or more coiled springs mounted on said plate, each spring having an extension of its lower end made in the direction of the adjacent standard and bent
15 near the standard to form a cross-bar transverse to the bolster, said extension passing thence under the bottom convolution of the spring and supporting the latter on the opposite side of the bolster
20 from the starting place of said spring extension and thence continued and bent to form a second cross-bar resting upon the bolster upon the opposite side of the spring from said first cross-bar, loops formed out
25 of the material of the base-plate engaging the cross-bars of said spring base-extensions whereby the latter are secured to the base-plate, and a bearing plate resting upon said
30 spring or springs.
- 30 3. The combination with a bolster having a standard near each of its ends, of a base-plate on said bolster having end notches to receive the standards, one or more coiled springs mounted on said base-plate, each
35 spring having an extension of its lower end made in the direction of the adjacent standard and bent near the standard to form a cross-bar transverse to the bolster, said extension passing thence under the bottom
40 convolution of the spring and supporting

the latter on the opposite side of the bolster from the starting place of said spring extension and thence continued and bent to form a second cross-bar resting upon the bolster upon the opposite side of the spring from
45 said first cross-bar, and loops formed out of the material of the base-plate and engaging each of said two opposite the cross-bars of base-extensions of each spring.

4. The combination with a bolster having
a pair of standards, one at each end, of a base-plate on said bolster having end notches to receive the standards, a pair of coiled springs mounted on said base-plate, each spring having an extension of its lower end
50 made in the direction of the adjacent standard and bent near the standard to form a cross-bar transverse to the bolster, said extension passing thence under the bottom convolution of the spring and supporting
55 the latter on the opposite side of the bolster from the starting place of said spring extension and thence continued and bent to form a second cross-bar resting upon the bolster upon the opposite side of the spring from
60 said first cross-bar, loops formed out of the material of the base-plate engaging the cross-bars of each base-extension, and a bearing plate having its ends notched to receive the
65 bolster standards, said plate resting upon said coiled spring.

In witness whereof, I have hereunto set my hand and seal at Indianapolis, Indiana, this 19th day of March, A. D. one thousand nine hundred and fourteen.

THADDEUS R. BAKER. [L. S.]
